UNITED STATES PATENT OFFICE.

WALTER W. LA CHANCE, OF CLEVELAND, OHIO, ASSIGNOR OF ONE-HALF TO
T. M. FOUTS, OF SAME PLACE.

CELL-DOOR-OPERATING DEVICE.

SPECIFICATION forming part of Letters Patent No. 508,026, dated November 7, 1893.

Application filed May 19, 1893. Serial No. 474,829. (No model.)

To all whom it may concern:

Be it known that I, WALTER W. LA CHANCE, a citizen of the United States, residing at Cleveland, in the county of Cuyahoga and 5 State of Ohio, have invented certain new and useful Improvements in Locking Devices for Cell-Doors, of which the following is a full, clear, and exact description.

My invention consists of a reciprocating bar 10 having one or more cell doors suspended therefrom by hangers and rolls and a corresponding number of springs and lever actuated latches, for locking said doors when closed; said bar being operated by means of 15 worm-gears and pinions.

The object of my improvement is to provide a device for closing and locking or unlocking and opening, either singly or all together, any number of cell doors, without entering the corridor where the cells are located.

My locking device can be operated with ease and expedition, from the guard-room of the prison by one person, who thereby avoids 25 all contact with the prisoners. The apparatus is simple in construction and operation, but effective, since it is beyond the power of a man unaided to force open from the inside a cell door secured with my device.

That my invention may be seen and fully understood by others, reference will be had to the following specification and annexed drawings forming a part thereof, in which—

Figure 1 is a side elevation of my locking device showing it in connection with two cell doors; Fig. 2, a horizontal sectional view on line Z, Z, Fig. 1; Fig. 3, a vertical, sectional view on line X, X, Fig. 4; Fig. 4, an enlarged side elevation of the reciprocating 35 bar and latch mechanism, with a portion of a cell door suspended from said bar; Fig. 5, a perspective view of one of the dogs and Fig. 6, a perspective view of the whole device showing it in connection with three doors, 40 two of said doors being open and the other closed.

Similar letters of reference designate like parts in the drawings and specification.

The reciprocating bar A, Figs. 1, 3, 4 and 50 6, passes over the cell doors B and rests upon the rolls C, Figs. 1 and 6, said rolls being at-

tached to the outside wall D of the cells by the pins C'. The bar A terminates at one end in the rack A' which projects into the closet E, Figs. 1, 2 and 6, to engage with the pinion F, Figs. 1 and 6. The pinion F is fast on the shaft F', the bearings of said shaft being bolted or otherwise secured to opposite sides of the closet E. Above the rack A' and the pinion F is the roll G, Figs. 1 and 6, on 60 the shaft G'. The shaft G' also has its bearings secured to opposite sides of the closet E, and the roll G holds the rack A' down on the pinion F. The dogs H, Figs. 1, 4, 5 and 6, are bolted to the bar A, at intervals, for the 65 purpose hereinafter described. The doors B are suspended from the bar A by the hangers I, Figs. 1, 3, 4 and 6. Each hanger I is provided with two rolls J which bear upon the top or upper edge of the bar A. The hanger I is of essentially the form shown in the drawings and has the lugs I' depending behind the bar A. The door B is securely attached to the lower terminals of the hanger lugs I'. Projecting from the edge nearest 70 the closet E, of each door B at the top, is the notched bar b. The doors B are provided with the handles B' by means of which any one of said doors may be closed from the cell corridor. The doors B are prevented from swinging forward at the bottom, by the stirp K, Figs. 1, 2 and 6.

The vertical shaft L, Figs. 1, 2 and 6, rests in the bearing M, at the base and is secured near the top by the horizontal hanger M'. 85 The bearing M, is fastened to the floor of the closet E and the hanger M' to one side of said closet. About midway on the shaft L is the worm-gear L' and above the hanger M' is the worm-gear L''. The horizontal shaft N, 90 Figs. 1, 2 and 6, with its bearings secured to the sides of the closet E, has attached thereto the pinion O meshing with the worm-gear L', and the hand-wheel P by means of which said shaft and pinion are rotated. The upper 95 worm-gear L'' meshes with the pinion F on the shaft F'. The door E' of the closet E opens into the guard-room of the prison or other convenient place.

Between the top of each door B and the 100 closet E is the latch Q, Figs. 1, 4 and 6, pivoted at Q' to the wall D. The latch Q, con-

sists of a vertical and a notched, horizontal arm as best shown in Fig. 4. The spiral spring R is fastened to the wall D above the bar A, and to the vertical arm of the latch Q for the purpose of retaining said latch in its normal position. The notched arm of the latch Q is adapted to engage the notched bar b of the door B, when said door is closed, and when so engaged prevents the door from being opened by any person within the cell. Before engaging with the latch Q, each of the notched bars b passes through an opening in the stop D', Figs. 1 and 6. The stop D' is a strip secured to the wall D for the purpose of limiting the movement of the door B in the direction of the closet E, and there may be one or more bolts b' on said door to register with openings in said stop for greater security. A rod S is pivotally connected to the top of the vertical arm of each latch Q and extends through the supporting brackets T into the closet E. In the closet E are the levers U, Figs. 1, 2 and 6, pivoted to the bracket V which is attached to the side of said closet, said levers terminating at the bottom, in the handles U'. The levers U correspond in number to the rods S and are pivotally connected with the ends of said rods.

In operation, the doors B being closed as represented in Fig. 1, one or more of the lever handles U' (according to the number of said doors which it is desired to open), are drawn away from the side of the closet E by a person within said closet, and the upper ends of the levers U force back the rods S, overcome the resiliency of the springs R, rock the latches Q and release the notched arms of said latches from the notched bars b. Now revolve the hand-wheel P in the direction of the arrow 1 in Fig. 40 1, and the bar A will be moved in the direction of the arrow 2, Fig. 1, through the medium of the vertical shaft L, with the worm-gears L' and L² thereon, and the pinions O and F. Since the doors B are suspended from the bar A it will be seen that they must travel with said bar, if free from the latches Q, while said bar readily passes beneath the hanger rolls J of the doors which have not been released. The dogs H, on the bar A, 45 are adapted to engage with the edges of the doors B, opposite the bars b, and, by reversing the motion of the hand-wheel P, said bar

and dogs will draw said doors over their respective openings until the notched bars b engage with the notched arms of the latches Q when the cells are again securely closed.

What I claim as my invention, and desire to secure by Letters Patent, is—

1. In a locking device for cell doors, a reciprocating bar terminating at one end in a rack and supported by rolls above one or more doors, said doors depending from said bar, in combination with the pinion F meshing with said rack, the roll G, a vertical shaft provided with two worm-gears, the upper of said worm-gears meshing with said pinion F, the pinion O on the shaft N meshing with the lower worm-gear and a hand-wheel for revolving said shaft N, in the manner substantially as and for the purpose set forth. 70

2. In a locking device for cell doors, one or more latches Q, corresponding in number to the doors, said latches pivoted to the front wall of the cells and adapted to engage and hold the notched bars b rigidly attached to said doors and springs arranged to retain said latches in their normal positions, in combination with a like number of rods and levers for rocking said latches from a distance, in the manner substantially as and for the purpose set forth. 75

3. In a locking device for cell doors, a rack terminating, reciprocating bar having dogs attached thereto, supported by rolls and supporting one or more doors by hangers and rolls, said rolls bearing on the upper edge of said bar, said doors provided with the notched bars b and bolts b', the strip K, stops D' and the bar actuating mechanism in the closet E, in combination with a corresponding number 80 of latches to said doors, the springs and rods attached to said latches, said rods passing through supporting brackets and into said closet and the levers U pivoted within the closet and provided with handles below the 95 pivotal points, in the manner substantially as and for the purpose set forth.

In testimony whereof I affix my signature in presence of two witnesses.

WALTER W. LA CHANCE.
